UNITED STATES PATENT OFFICE.

FREDERICK H. APEL, OF ATHOL SPRINGS, NEW YORK, ASSIGNOR TO LIVINGSTON
ARTIFICIAL LIMB COMPANY, OF NEW YORK, N. Y., A CORPORATION OF DELAWARE.

ARTIFICIAL LIMB.

Application filed August 21, 1924. Serial No. 733,331.

This invention relates to an artificial limb and more particularly to an article of this character which is intended to be applied to the stump of an arm and serve as a substitute for a hand, the several parts of which are so organized as to permit of simulating the usual functions of the wrist, palm, fingers and thumb of the hand.

It is the object of this invention to produce an artificial limb of this character whereby the movements of the several members are effected by means which are of simpler construction, more easily operated and have not only a greater capacity for holding various articles but are also more natural in appearance and therefore conceal to a greater extent that the hand is not real.

In the accompanying drawings:

Figure 1, is a vertical longitudinal section of an artificial hand embodying my invention.

Figure 2, is an elevation, partly in section, of the artificial limb viewed from the palm side of the hand.

Figure 3, is a fragmentary view similar to Figure 1, but showing one of the fingers in a closed or folded position relative to the palm.

Figure 4, is a fragmentary perspective view showing the manner in which a pencil or like object is grasped between the thumb and the fingers of the hand in accordance with my invention.

Figure 5, is a vertical transverse section of the joint between the wrist and palm similar to the lower part of Figure 2, but in a different position.

Figure 6, is a vertical section taken on line 6—6, Figure 5.

Figure 7, is a horizontal section taken on the correspondingly numbered line in Figure 1.

Similar characters of reference indicate like parts in the several figures of the drawings:

In its general organization this artificial limb comprises a hollow wrist 10 which may be attached to the stump of the arm in any suitable manner, a hollow palm 12 which is pivotally connected with the wrist, a plurality of articulated fingers 11 mounted on the front end of the palm so as to be capable of folding inwardly and unfolding outwardly relatively thereto, and a thumb 13 pivotally mounted on one side of the palm.

The several members are made of any suitable material, preferably metal, and covered in any approved manner.

The wrist and palm are adjustably connected so that the palm may be tilted or turned relatively to the wrist, the means for this purpose shown in the drawings being constructed as follows:

The numeral 14 represents a hollow spherical socket arranged at the front end of the wrist and 15 a hollow ball arranged on the rear end of the palm and rotatable to a limited extent in all directions on the interior of the spherical socket. On its inner side this socket is provided with a plurality of longitudinal grooves 16 which are arranged in a circumferential row extending latitudinally around the socket. Arranged in line with each of these grooves and extending from the bottom of the same to the periphery of the socket is a longitudinal row of locking openings 17. The numeral 18 represents the inner arm of a U-shaped locking lever or latch which is arranged within the hollow ball and 19 the outer arm of the same which extends from the upper end of the inner arm outwardly through an opening 20 in the palm and rearwardly along the outer side of the socket. This lever is pivoted at the outer ends of its arms to the inner side of the ball adjacent to the palm by a pivot screw or pin 21 mounted transversely on the ball and palm and passing through a hub 22 on this lever so that the arms of the same are movable radially toward and from the peripheries of the ball and socket. The inner arm of the locking lever is arranged in a longitudinal guide slot 23 in the ball and provided at its extremity with one or more teeth 24, preferably three, which are adapted to engage with one or another of the openings in the several rows on the socket for the purpose of locking the palm in whatever position the same may be turned relatively to the wrist. This locking lever is yieldingly held in its outward or operative position by a spring having a coil 25 surrounding the pivot pin 21 and having the arms 26 at its opposite ends for engaging the palm 12 and the lever 18.

When it is desired to adjust the palm on the wrist the outer arm 19 of the locking lever is pressed inwardly so as to disengage its toothed inner arm from the respective

locking openings of the socket and then the ball and palm are turned into the desired position relatively to the wrist. If it is only desired to tilt the palm at a different angle relatively to the wrist the locking lever need only to be pressed inwardly sufficiently to disengage its teeth from the respective locking openings but not out of the groove associated therewith whereby the latter will serve as a guide for retaining the palm and wrist in the position while tilting the same the required extent relatively to each other. Upon reaching the desired position the inward pressure on the locking lever is relaxed and its teeth are permitted to engage the desired locking openings, thereby holding the palm in the adjusted position. When, however, the palm is to be turned about its longitudinal axis for changing the relation of the same and the wrist accordingly the locking lever is pressed inwardly sufficiently to disengage the same from the respective locking openings and then engaged with the desired groove and the companion locking openings thereof for holding the palm in this changed position.

Obviously therefore, by means of these two directions in which the palm may be shifted relatively to the wrist, it is possible to obtain substantially universal adjustment of the palm relative to the wrist and thus place the hand in whatever position is best suited for any particular requirements. The outer side of the outer arm of this locking lever is preferably provided with a covering of serrated rubber, or the like, in order to prevent the same from slipping when engaged by the other hand or object which is utilized for operating the wrist and palm adjusting device.

All the fingers and their operating mechanism are identical in construction and the following description of one will there apply to all of them:—

The numeral 28 represents the inner or first finger section which is pivotally connected at its rear end with the front end of the palm so as to be capable of swinging inwardly and outwardly relatively thereto, this pivotal connection being preferably effected by a pivot rod 29 extending through the inner parts of the several inner finger sections and supported between these sections by brackets 30 on the palm while its opposite ends are supported on the sides of the palm, as shown in Figures 1 and 2. The second or intermediate section 31 of each finger is pivotally connected by a pin 32, or otherwise, at its inner end with the outer end of the respective inner section, and the outer or third section 33 of the finger is pivotally connected with the outer end of the intermediate section by a pin 34, or the like.

The first or inner finger section may be turned about the pivot rod 29, the second

finger section may be turned on the first finger section, and the third finger section on the second finger section by a lever link 35 pivotally connected at its inner end by a pivot 129 with the front end of the palm outside of the pin 29, and pivotally near its front end by a pin 36 with the second finger section inside of the pivot 32, and an outer link 37 pivotally connected by a pin 38 with the outer end of the lever link 35 and pivotally connected at its outer end with the third finger section by a pin 39 inside of the axis of the latter, as shown in Figures 1, 2 and 3. Upon rocking the inner or first finger section on the palm the linkage connecting the several finger sections with the palm will cause these sections to unfold or open into the position shown in Figures 1 and 2, when the first section is swung outwardly, and these several finger sections to fold or close relatively to each other and the palm when the first finger section is swung inwardly, as shown in Figure 3. These finger sections are yieldingly held in their closed or folded position by a spring having a coil 40 surrounding the pivot pin 29 and having arms 41, 42 at its opposite ends engaging with an abutment 142 on the first finger section and an abutment arranged on the palm and consisting in the present instance of a rod 43 extending across the palm and supported on the sides thereof and on said brackets 30. The unfolding or opening of the finger sections and the locking of the same in position is effected by a shifting or adjusting bar 44 arranged lengthwise in the first and second finger sections and in the palm and pivotally connected at its outer end with the lever link, preferably by mounting this bar on the pin 36, and provided on the outer longitudinal edge of its inner part with a longitudinal row of ratchet teeth 45, a ratchet segment 46 surrounding the pivot rod 29 and connected by a pin 47 or otherwise with the adjacent part of the inner finger section so as to be compelled to turn therewith, a spring which operates to turn the adjusting bar toward said ratchet segment and holds the ratchet teeth of said bar yieldingly in engagement with those of said segment, said spring having a coil 48 surrounding the pivot pin 36 and having its opposite ends connected with the lever link and said adjusting bar, and an operating line 49 passing over a guide pulley 50 on the rod 43 and having one stretch connected with the inner end of the adjusting bar while its other stretch passes through an opening 51 in the palm to the exterior thereof so that the same can be manipulated as desired.

Normally each finger is held closed by its spring 40 and is locked against opening by the locking bar 44 engaging the locking segment 46. To use this finger the same is first opened, this being done by pulling on the

line 49. The first part of this pull disengages the locking bar from the segment and the further pull on the same unfolds the finger. The finger is now placed adjacent to the object to be grasped and then the pull on the line is released which permits the spring 40 to close the finger until it bears against the object. During this time the locking bar slides over the ratchet segment 10 as far as the closing movement of the finger permits and in whatever position the finger comes to rest it is locked in this position and holds the object by reason of the locking bar being held in engagement with the locking 15 segment by the spring 48.

The thumb 13 comprises an inner section 52 which is pivotally connected by a pin 53 with the rear part of one side of the palm and an outer section 54 pivotally connected 20 by a pin 55 with the inner section so that these sections are capable of being folded inwardly and unfolded outwardly relatively to the palm. The inner thumb section is yieldingly held in its open or unfolded position by a spring 56 having its coil around the pin 53 and its ends engaging respectively with the inner thumb section and the palm, as shown in Figures 1 and 4. The outer thumb section is folded or closed when 25 the inner thumb section is opened, as shown in Figure 1, and the same is unfolded or opened when the inner thumb section is folded or closed, as shown in Figure 4, by means of a shifting link 57 pivotally connected at its inner end by a pin 58 with the palm inside of the pivotal connection between the inner thumb section and the palm, while the outer end of this link is connected 30 by a pivot pin 59 with the outer thumb section beyond the pivotal connection between the outer and inner thumb sections.

The inner thumb section may be locked in a more or less inwardly folded or closed position by means of an angular latch, catch or locking lever having an upper transverse arm 60 which is pivoted at its outer end on the shifting link 57 by means of a pin 61, and a lower longitudinal arm 62 projecting from the inner end of said upper arm longitudinally rearward and laterally through an opening 63 in the lower part of the palm, a plurality of hooks or teeth 64 adapted to engage an abutment on the palm having the form of a pin 65, and a spring 66 connecting said latch and inner thumb section and operating to hold the toothed inner arm of said latch yieldingly in engagement with said abutment. The teeth of the latch are inclined outwardly so that upon pressing the inner thumb section inwardly the same will trip with one of its hooks or teeth after another over the abutment 65 and when this inward pressure against the thumb ceases the same will be held by the latch in whatever position the same may be in. Upon

pressing inwardly against the longitudinal arm of the angular latch the same is disengaged from the abutment 65 and this permits the same to be swung outwardly into its open or unfolded position.

The fingers and thumb are by the means above described capable of being closed more or less and thus adapt themselves to various shapes of articles for securely holding the same.

Means are provided for enabling a pencil 70 or similar article to be securely held between the tip or outer section of the thumb and the tips or outer sections of the fingers and permit of writing with the same in a 80 manner closely resembling the operation of a natural hand.

For this purpose an abutment or stop 67 is mounted on the tip or outer section of the thumb so as to be capable of projecting into 85 an operative position from the inner side thereof and to be retracted within this side. In the preferred construction this abutment forms the upper arm of a lever which is arranged lengthwise in the outer end of the 90 hollow tip or outer section of the thumb and pivotally mounted thereon by a transverse pin 68 and a spring 69 is provided which turns this lever and holds the same yieldingly in the position in which this abutment 95 projects laterally from the inner side of the thumb tip. The movement of the abutment lever in this direction is limited by engagement of its lower arm 72 engaging with the inner side of the thumb tip. When it is desired to hold a pencil or the like the tip or outer section of the middle or second finger is folded against this abutment and firmly held by the same against further backward movement along the thumb. The pencil, pen or similar article 70 is then placed along the outer end of the thumb and that side of the middle finger which faces toward the first finger, and then the first finger is folded and its tip or outer section engaged 100 with that side of the pen or the like opposite where the latter is engaged by the second finger, as shown in Figure 4, thereby producing a three point grip on the pencil and holding it securely while the same is 105 used for writing, and also permitting other like functions to be performed with ease and facility. Release of the pencil or other tool is effected by simply disengaging the finger and thumb from the same. Upon 110 pressing the inner side of the thumb tip or outer section against an object when not holding a pencil the abutment simply recedes within the tip and does not interfere 115 with its use.

From the foregoing it will be apparent that in this artificial hand the palm, fingers and thumb can be easily and conveniently shifted into various positions at will and thus render the same less conspicuous and 120 125 130

less embarrassing to the person using the same and also enabling the same to be used to a considerable extent for practical purposes and to simulate the movements and positions of a natural hand.

I claim as my invention:-

1. An artificial limb comprising a palm, a wrist, and means for adjustably connecting said palm and wrist comprising a spherical socket member, a spherical ball member turnable in said socket, one of said members being connected with the wrist and the other with the palm, said socket being provided with a longitudinal row of openings, and a locking device mounted on said ball and adapted to engage with one or another of said openings.
2. An artificial limb comprising a palm, a wrist, and means for adjustably connecting said palm and wrist comprising a spherical socket member, a spherical ball member turnable in said socket, one of said members being connected with the wrist and the other with the palm, said socket being provided with a plurality of longitudinal rows of openings arranged at different points latitudinally thereof, and a locking device mounted on the ball and adapted to engage with one or another of said openings.
3. An artificial limb comprising a palm, a wrist, and means for adjustably connecting said palm and wrist comprising a spherical socket member, a spherical ball member turnable in said socket, one of said members being connected with the wrist and the other with the palm, said socket being provided with a plurality of longitudinal grooves at different points latitudinally thereof and a longitudinal row of openings in line with each of said grooves, and a locking device mounted on said ball and adapted to engage one or the other of said grooves and one or another of the openings in line therewith.
4. An artificial limb comprising a palm, a wrist, and means for adjustably connecting said palm and wrist comprising a spherical socket member, a spherical ball member turnable in said socket, one of said members being connected with the wrist and the other with the palm, and a locking device comprising a lever pivoted on one of said members and having an inner arm adapted to hold said ball and socket against relative movement and an outer arm adapted to be manipulated.
5. An artificial limb comprising a palm, a wrist, and means for adjustably connecting said palm and wrist comprising a spherical socket member, a spherical ball member turnable in said socket, one of said members being connected with the wrist and the other with the palm, and a locking device comprising a U-shaped lever pivoted on said ball and having an inner arm arranged within the ball and adapted to pass outwardly

through said ball and socket for holding the same against relative movement and an outer arm arranged outside of the socket and adapted to be manipulated.

6. An artificial limb comprising a palm, a wrist, and means for adjustably connecting said palm and wrist comprising a spherical socket member, a spherical ball member turnable in said socket, one of said members being connected with the wrist and the other with the palm, and a locking device comprising a U-shaped lever pivoted on said ball and having an inner arm arranged within the ball and adapted to pass outwardly through said ball and socket for holding the same against relative movement and an outer arm arranged outside of the socket and adapted to be manipulated and a spring for yieldingly holding said lever in its operative position.

7. An artificial limb comprising a wrist, a palm, and means for adjustably connecting said wrist and palm comprising a spherical socket arranged on the wrist and having a plurality of longitudinal rows of openings arranged at different points latitudinally thereof, a ball mounted on the wrist and rotatable within said socket and having a longitudinal slot, a locking lever pivoted within said wrist and having an inner arm arranged within said ball and provided with a toothed extremity which is guided in said slot and adapted to engage with one or another of said openings in the socket and an outer arm arranged adjacent to the periphery of said socket, and a spring operating to hold said locking lever yieldingly in its operative position.

8. An artificial limb comprising a palm, an inner finger section pivoted to the palm, an intermediate finger section pivoted to the inner finger section, a link pivotally connected at its outer end with said intermediate finger section and pivotally connected at its inner end with the palm at a point adjacent to the pivotal connection between said palm and inner finger section, a ratchet segment connected with the inner finger section and arranged around the pivotal connection between said palm and inner finger section, and an adjusting bar pivotally connected at its outer end with said intermediate finger section and provided on its inner part with ratchet teeth adapted to engage with said ratchet segment.

9. An artificial limb comprising a palm, an inner finger section pivoted to the palm, an intermediate finger section pivoted to the inner finger section, a link pivotally connected at its outer end with said intermediate finger section and pivotally connected at its inner end with the palm at a point adjacent to the pivotal connection between said palm and inner finger section, a ratchet segment connected with the inner finger sec-

tion and arranged around the pivotal connection between said palm and inner finger section, an adjusting bar pivotally connected at its outer end with said intermediate finger section and provided on its inner part with ratchet teeth adapted to engage with said ratchet segment and an operating line connected with said adjusting bar.

10. An artificial limb comprising a palm, an inner finger section pivoted to the palm, an intermediate finger section, pivoted to the inner finger section, a link pivotally connected at its outer end with said intermediate finger section and pivotally connected at 15 its inner end with the palm at a point adjacent to the pivotal connection between said palm and inner finger section, a ratchet segment connected with the inner finger section and arranged around the pivotal connection between said palm and inner finger section, an adjusting bar pivotally connected at its outer end with said intermediate finger section and provided on its inner part with ratchet teeth adapted to engage with said ratchet segment and spring for yieldingly holding said inner finger section yieldingly in its closed position.

11. An artificial limb comprising a palm, an inner finger section pivoted to the palm, an intermediate finger section pivoted to the inner finger section, a link pivotally connected at its outer end with said intermediate finger section and pivotally connected at 35 its inner end with the palm at a point adjacent to the pivotal connection between said palm and inner finger section, a ratchet segment connected with the inner finger section and arranged around the pivotal connection between said palm and inner finger section, an adjusting bar pivotally connected at its outer end with said intermediate finger section and provided on its inner part with ratchet teeth adapted to engage with said ratchet segment and a spring for yieldingly holding the toothed part of said adjusting bar in engagement with said ratchet segment.

12. An artificial limb comprising a palm, an inner thumb section pivoted to said palm, an outer thumb section pivoted to the inner thumb section, a link pivotally connected at 50 one end with the outer thumb section and pivoted at its inner end on said palm, a

catch having an inner arm pivoted on said link and provided with locking teeth and an outer arm passing through said palm to the exterior thereof, and an abutment arranged on said palm and adapted to be engaged by the teeth on the inner arm of said catch.

13. An artificial limb comprising a palm, an inner thumb section pivoted to said palm, an outer thumb section pivoted to the inner thumb section, a link pivotally connected at one end with the outer thumb section and pivoted at its inner end on said palm, a catch having an inner arm pivoted on said link and provided with locking teeth and an outer arm passing through said palm to the exterior thereof, an abutment arranged on said palm and adapted to be engaged by the teeth on the inner arm of said catch and a spring operating to yieldingly hold said inner thumb section in its open position.

14. An artificial limb comprising a palm, an inner thumb section pivoted to said palm, an outer thumb section pivoted to the inner thumb section, a link pivotally connected at one end with the outer thumb section and pivoted at its inner end on said palm, a catch having an inner arm pivoted on said link and provided with locking teeth and an outer arm passing through said palm, to the exterior thereof, an abutment arranged on said palm and adapted to be engaged by the teeth on the inner arm of said catch and a spring for holding said catch yieldingly in engagement with said abutment.

15. An artificial limb comprising a palm, a plurality of fingers pivoted on the palm, a thumb pivoted on the palm, and an abutment movably mounted on the outer part of said thumb and adapted to be engaged by one of said fingers for stopping the inward movement of the latter thereon.

16. An artificial limb comprising a palm, a plurality of fingers pivoted on the palm, a thumb pivoted on the palm, an abutment pivotally mounted on the thumb, and adapted to be projected therefrom in a position to be engaged by one of said fingers for stopping the inward movement of the latter when the same are engaged, and a spring for yieldingly holding said abutment in its operative position.

FREDERICK H. APEL.
